UNITED STATES PATENT OFFICE

NEAL W. DORMAN, OF TOLEDO, OHIO, ASSIGNOR TO THE TOLEDO MACHINE & TOOL COMPANY, OF TOLEDO, OHIO, A CORPORATION OF OHIO

SIZING, COINING, OR SQUEEZING ATTACHMENT FOR POWER PRESSES

Application filed May 12, 1928. Serial No. 277,167.

In manufacturing shackles, pitmen, eccentric straps, and other machine elements which are adapted to move in a plane between two adjacent surfaces, it is important that the thickness of such elements be gaged with the utmost accuracy, in order that they may move freely when assembled, without any appreciable transverse play. Recently, it has become a common practice to size such elements in a power press by a process known as squeezing. In this process, work-engaging pressure members with flat or formed faces take the place of the usual punching or shaping dies, such pressure members being accurately gaged to squeeze the work piece to the desired thickness.

In carrying out the squeezing process, as above described, it frequently happens that the work piece will stick to the upper squeezing or pressure member and be lifted thereby, and sometimes the operator, without noticing this, will insert the next work piece beneath the piece already in the press. The result is quite disastrous, causing the two pieces to be squeezed instead of one. The tremendous pressure thus developed imposes a strain on the machine, which throws it out of adjustment, if it does not wreck it altogether.

With the above features in mind, the object of the present invention is to make it impossible for such conditions to occur, by so constructing the squeezing or pressure members that a work piece cannot be inserted between them until the preceding piece has been removed. This object is accomplished by providing a bottom pressure member of novel and improved construction, which is adapted to be attached to a squeezing press of the type heretofore used, without any alteration in the latter.

The specific construction of the invention, and the advantages resulting therefrom, will be more particularly described in connection with the accompanying drawing, in which

the single figure represents a portion of a power press, partly in elevation and partly in section, with the invention applied thereto.

In the drawing, the numeral 1 indicates the frame of a power press, which may be of any suitable construction having a bed 2, preferably with a bolster 3 secured thereon, and with upright portions 4 extending upwardly therefrom and constituting guides for a power operated plunger 5. The plunger 5 is constructed to receive a die or pressure block 6 and an opposing die or pressure block 7, with a hardened face 8, is mounted on the bolster 3. In accordance with the invention, an intermediate block 9 with a hardened face 10, is slidably mounted on vertical guides 11, which extend upwardly from the bolster 3. Surrounding each guide 11 is an expansile coil spring 12 which bears against the respective seats 13 and 14 formed on the end portions of the blocks 7 and 9. These springs are strong enough to raise the block 9 as the plunger 5 moves upwardly, the upward movement of the block 9 being limited by suitable stops 15 adjustably held on the upper ends of the guides 11 by lock nuts 16, located within recesses 17 in the block 7.

The work, as indicated at 18, is adapted to be squeezed between opposed faces of the blocks 7 and 9, respectively. Stops 19 are located at opposite ends of the block 7 and are accurately gaged to the thickness desired, and the stroke of the plunger 5 is also adjusted to squeeze the piece 18 to the desired thickness. The block 9 is so constructed and mounted that, when it is in its uppermost position, it will afford ample clearance for the piece 18 to be inserted, but the space between the faces of the blocks 7 and 9 will be so restricted that it will be impossible to insert a second work piece 18 until the preceding piece has been removed. At the same time the block 9 is arranged to transmit the full power of the plunger 5 to the piece to be squeezed.

While I have shown and described in detail only one specific embodiment of the invention, it will be understood that the same may be modified to a considerable extent without departing from the scope of the invention as claimed.

5 What I claim is:

1. In a power press, the combination with a stationary bed, a pressure member movable toward and away from the same, and blocks 10 for attachment respectively to said bed and said pressure member to gage the thickness to which the work piece is to be squeezed, of vertical guide means secured in and extending 15 upwardly from the lowermost block, an intermediate block disposed between the first mentioned blocks and mounted for vertical sliding movement on said guide means, resilient means tending to move the intermediate 20 block upwardly to its uppermost position when it is released by the upward travel of the pressure member, and means for positively limiting the upward movement of the intermediate block, said last mentioned means 25 being secured to and adjustable vertically on said guide means.

2. In a power press, the combination with a stationary bed, a pressure member movable toward and away from the same, and blocks 30 for attachment respectively to said bed and said pressure member to gage the thickness to which the work piece is to be squeezed, of vertical guide means, an intermediate block disposed between the first mentioned blocks 35 and mounted for vertical sliding movement on said guide means, means for reciprocating said pressure member, means for causing the intermediate block to move with the pressure member throughout the lower part of its stroke, and means for positively limiting the 40 upper position of the intermediate block so that the space between said intermediate block and the lower block is less than twice the thickness of the piece to be squeezed.

45 3. In a power press, the combination of a stationary bed, a block mounted thereon, vertical guide means secured to and extending upwardly from said block, a movable block guided on said guide means, a pressure member operable to force the movable block downwardly to operate on the work, stops on said 50 guide means to limit the upward movement of the movable block, and spring means to force the movable block against said stops as said 55 pressure member is raised, said stops being so located that the distance between the faces of the blocks is less than twice the thickness of the work piece, when the movable block is in its highest position.

60 4. A squeezing device comprising a stationary bed, a block mounted thereon, a vertically movable plunger above said block, a vertically movable intermediate block between the plunger and the lower block, said 65 blocks having opposed flat faces, stops of pre-

determined gage on the face of the lower block to positively limit the minimum distance between said faces to the desired thickness of the workpiece, means positively limiting the maximum separation of said faces to less than twice the thickness of the workpiece, and means for maintaining the intermediate block in its uppermost position when the plunger is raised out of engagement therewith.

70 75 In testimony whereof, I have hereunto signed my name to this specification.
